CLAIM

I claim the ornamental design for a feet throw, as shown and described.

DESCRIPTION

FIG. 1 is a bottom view of the feet throw showing the foot pocket;

FIG. 2 is an additional bottom view with the foot pocket folded over to show the interior surface and a corner folded forward to show the top surface; and,

FIG. 3 is a top view.

The broken lines shown in the drawing disclosure represent stitching and form a part of the claim.
